UNITED STATES PATENT OFFICE

2,665,890

POWDER MIXER

Arthur L. Hall, Memphis, Tenn.

Application January 25, 1952, Serial No. 268,250

1 Claim. (Cl. 259—89)

1

This invention relates to a mixing device for mixing dry powdered or granular material.

An object of this invention is to provide a mixing device for mixing powders, such as face powders or for mixing self-rising flour, whereby the ingredients making up the material will be thoroughly mixed together.

Another object of this invention is to provide a mixing device which is adapted to be rotated during the mixing operation and is constructed in the form of a wobbling housing which is adapted to throw the material about the interior thereof during the rotation of the housing.

A further object of this invention is to provide a mixing device which can be used for mixing various kinds and types of powdered or granular material, and may be rotated either by means of a hand crank or a power means.

With the above and other objects in view, my invention consists in the arrangement, combination and details of construction disclosed in the drawings and specification, and then more particularly pointed out in the appended claim.

In the drawings:

Figure 1 is a detailed side elevation of a mixer constructed according to an embodiment of this invention.

Figure 2 is a plan view of the device.

Figure 3 is a side elevation partly broken away and in section of the rotary mixer housing.

Figure 4 is a plan view of the housing removed from the base.

Figure 5 is a sectional view taken on the line 5—5 of Figure 3.

Referring to the drawings, the numeral 10 designates generally a base frame structure which includes a base member 11, uprights 12, with horizontal upper bars 13 carried by the uprights 12 and connected together by means of end connection bars 14. A mixer housing, generally designated as 15, is rotatably carried by the base 10 and is formed of a polygonal central housing or body 16 which, as shown in Figure 5, is square in transverse section.

The central body 16 has extending diagonally therethrough from one edge to a diagonal opposite edge and from an upper corner to a lower corner a shaft 17. The shaft 17 is journalled in bearings 18 carried by the upper frame bars 13, and one end of the shaft 17 has a grooved pulley 19a secured thereto. The diagonal mounting of the shaft 17 through the body 16 provides for supporting the body 16 on an angle to the vertical so as to produce a wobbling motion to the housing as the latter is rotated by the shaft 17.

2

The body 16 has extending from the opposite ends thereof tapered funnel-like members 19 and 20. The funnel-like members 19 and 20 are oppositely disposed being formed with one side 21 thereof coplanar with a side of the body 16 and also having outwardly inclined walls or sides 22 and 23. The outer end of each funnel shaped receptacle 19 terminates in a cylindrical neck 24 on which a cap 25 is threadably mounted. The body 16 has disposed on the inner side thereof oppositely disposed pairs of longitudinally extending baffle plates 26. These baffle plates 26 will be disposed on an inclination to the vertical due to the inclined mounting of the housing 15 on the shaft 17.

It will be understood that, if desired, a hand crank or the like may be secured to the shaft 17 for manually rotating the housing 15 if desired. In the present instance, a power member 27 is carried by the base 10 and includes a grooved pulley 28 about which an endless belt 29 engages, with belt 29 also engaging about pulley 19a.

The mixing device hereinbefore described is designed for mixing of face powders, self-rising flour or other powdered material. The housing 15 is partially filled with several powdered ingredients by disposing one of the funnel shaped members 19 and 20 uppermost and removing the cap 25, which is uppermost. The housing 15 may then be rotated at the desired speed, and in the rotation of the housing 15, the material will slide down into the funnel shaped member which is lowermost, passing over the inclined baffles 26 and into the lower funnel shaped member 20.

The housing 15 is preferably rotated at a relatively slow rate so that the material will not be held in the receptacle or funnel shaped members 19 and 20 by centrifugal force. This mixing device will provide a means whereby a powdered ingredient; such as face powder or self-rising flour; may be thoroughly and evenly mixed together in a dry state and within a relatively short period of time. When the powder has been thoroughly and intimately mixed as to the ingredients thereof, the mixture may then be removed from the housing 15 by disposing the same in a position where one of the caps 25 is lowermost. The lower cap is then removed and the powder will gravitatingly flow from the lower funnel shaped member into the desired receiver.

I do not mean to confine myself to the exact details of construction herein disclosed, but claim all variations falling within the purview of the appended claim.

What is claimed is:

A dry powder mixer comprising a rotatably mounted hollow body which has a pair of opposed open ends, a tapered funnel-shaped member having inclined walls and extending from each end in communication therewith, the apex of one member being diagonally disposed with respect to the apex of the other member and the apex of one member being in alignment with one side of the body while the apex of the other member is in alignment with the opposite side of the body, the inclined walls of said members serving to shift powder transversely of the body from one apex to the other during rotation of the body, removable closures on the apex of each member, a shaft fixed to and extending through the body, said shaft extending through dia-

nally opposite corners of the body and having its longitudinal axis lying on a line oblique to a line joining the apices of the members, said body being disposed on an oblique angle to said shaft, opposed pairs of baffles in said body and extending axially between the open ends, and means rotatably supporting said shaft.

ARTHUR L. HALL.
